Attorney

UNITED STATES PATENT OFFICE.

BARTH E. BARTHOLOMAE, OF PITTSBURGH, PENNSYLVANIA.

SHOE HORN.

Application filed July 13, 1928. Serial No. 292,574.

This invention relates to improvements in shoe horns of the limp or flexible and non-resilient type.

In the use of the ordinary limp shoe horn, much inconvenience and annoyance frequently arise from the fact that the user is unable to hold it firmly and manipulate it properly to accomplish the work. Being obliged to grasp it with the thumb and finger, with the thumb usually in front, the thumb is always in the way of convenient use so as to seriously interfere with starting the heel in the shoe. It is also difficult to obtain a secure hold to withdraw such a shoe horn from the shoe after the foot is in place, and such hold frequently slips, causing annoyance to the user.

The primary object of the present invention, therefore, is to obviate these difficulties by constructing a shoe horn so that it may be held in such a manner that the thumb will not interfere with the work and the heel will be forced more readily into the shoe by its use, and so that the shoe horn may be more readily withdrawn after the foot is in place in the shoe, without danger of losing the hold on the shoe horn.

A more specific object is to provide a limp shoe horn with a handle or finger loop in a simple and economical manner.

Still another object is to provide the finger loop or handle so that it will be efficient and durable.

A still further object is to provide means for facilitating engagement of the finger in the finger loop or handle of the shoe horn.

Other objects and advantages will appear as the nature of the invention is better understood, and the same consists in the novel form, combination and arrangement of parts hereinafter more fully described, shown in the accompanying drawing and claimed.

In the drawing:

Figure 1 is a rear elevational view of a shoe horn embodying the present invention.

Figure 2 is a front elevational view thereof.

Figure 3 is an edge elevational view looking toward the left of Figure 2; and

Figure 4 is a plan view of the blank from which the shoe horn of Figure 1 is formed.

Referring more in detail to the drawing, the present shoe horn is preferably formed from a blank of the shape shown in Figure 4, including a body having an enlarged lower or heel engaging portion 5 of the usual or any preferred shape, and a shank portion 6

at the upper end of the heel engaging portion 5 and preferably narrower than the latter. The blank further embodies an integral extension or flap 7 on the upper end of the shank 6, and conforming in shape substantially to the shape of said shank but normally inverted relative thereto.

In forming the shoe horn from the blank shown in Figure 4 and above described, the extension or flap 7 is folded backwardly onto the shank portion 6 of the body of the shoe horn upon a transverse fold line 8 forming the line of connection between the shank 6 and said extension or flap 7. The lower or free end edge of the extension or flap 7 is then stitched to the body of the shoe horn as at 9 so that the shank 6 and extension 7 form a relatively large handle or loop in which the finger may be effectively engaged for use in withdrawing the shoe horn from the heel of the shoe after the foot is in place in the latter. It will be apparent that with the finger engaged in the loop, the thumb of the user may be disposed out of the way so as to not interfere with the use of the shoe horn.

The shoe horn is flat and flexible, and as the blank is thin and stamped out of any suitable material, such as leather, in flat form with the extension 7 integral with the body, economical manufacture is had and a durable construction is presented when the extension is folded backwardly and stitched to the body of the shoe horn as above described.

To facilitate engagement of the finger in the handle or finger loop whether using the right or left hand, I preferably provide a notch 10 in one side edge of the shank 6 and a similar notch 11 in the opposite side edge of the extension 7. These notches are preferably curved and elongated, and the walls thereof extend inwardly of the adjacent side edge portions of the extension 7 and shank 6 respectively. It is therefore evident that by engaging the finger in one of the notches 10 or 11, the shank and extension may be separated to facilitate the entrance of the finger into the loop or handle. The extension 7 and the shank 6 may be pierced with registered openings 12 to facilitate hanging of the shoe horn upon a hook, if desired, when not in use.

As the shoe horn is made of flexible and non-resilient or limp material, it may be readily rolled or folded into small compass for being conveniently carried in the pocket, a vanity case or the like. Furthermore, due

to the softness of the flexible or limp material, the shoe horn will withstand severe usage, will not wear through thin materials or scratch polished surfaces, and will not cause 5 discomfort to the user such as is experienced by the use of stiff shoe horns made of metal or the like. As the heel engaging portion of the shoe horn is limp, it will readily shape itself to the heel, thereby enabling the shoe to 10 be easily slipped on the foot.

It might be noted that, due to the flat form of the heel engaging portion of the body, its front surface may be effectively utilized for advertising purposes, while its 15 rear surface may be used for the trade name and other desirable information.

As the shoe horn is used in the same general manner as heretofore practiced in connection with other shoe horns of this general type, it 20 is believed that its manner of use and advantages will be readily appreciated and understood without more detail comment thereon.

Minor changes may be made without departing from the spirit and scope of the invention as claimed. 25

What I claim as new is:

1. A shoe horn formed from a single piece of flat flexible and non-resilient material and comprising a body having a lower heel engaging portion and an upper shank, and an extension integral with the upper end of the shank folded backwardly onto and secured at its lower end to the latter to form in conjunction with said shank a finger loop, said shank and said extension being of similar 30 shape and respectively having finger notches in the opposite side edges thereof. 35

2. A limp shoe horn formed from a single piece of flexible non-resilient material to include a body and an extension on the upper 40 end of the body, said extension being folded backwardly onto the upper end portion of said body stitched at its lower edge to the latter to form a finger loop, a portion of said finger loop having a notch in one side edge 45 thereof to facilitate engagement of a finger in the loop.

In testimony whereof I affix my signature.

BARTH E. BARTHOLOMAE.
